UNITED STATES PATENT OFFICE

157,590

GAME BOARD

Antonio Diaz Hernandez, Catano, San Juan
County and Territory of Puerto Rico

Application June 29, 1948, Serial No. 147,258

Term of patent 14 years

(Cl. D34—5)

To all whom it may concern:

Be it known that I, Antonio Diaz Hernandez, a citizen of the United States of America, residing at Catano, in the county of San Juan and Territory of Puerto Rico, have invented a new, original, and ornamental Design for a Game Board, of which the following is a specification, reference being had to the accompanying drawing, forming a part thereof wherein:

I claim:

The ornamental design for a game board, as shown.

ANTONIO DIAZ HERNANDEZ.
